METHOD AND APPARATUS FOR MULTIPLEX TELEGRAPHY

Rudolf Heidester, Ulm (Danube), Germany, assignor to Telefunken G.m.b.H., Berlin, Germany

Application October 25, 1955, Serial No. 542,724

Claims priority, application Germany October 28, 1954

5 Claims. (Cl. 178—51)

The invention relates to multiplex telegraphy, i.e. to a method and apparatus of receiving two telegraphic signals transmitted concurrently by frequency-shift mark and space-transmission employing four degrees of shift symmetrically arranged about a center channel frequency.

It has been known in the transmission of telegraphic intelligence, for example in the radio transmission of such intelligence, to use frequency-shift methods. In these methods the mark and space signals are produced by shifting from one frequency to another. Altogether four different frequencies are required to transmit two separate telegraphic messages by a single transmitter, whereby only a single frequency is transmitted at any particular instant. Several of such methods have been known. In the Twinplex system, also known as the Diplex system, there is assigned to the one channel a certain frequency shift and to the other half of such frequency shift.

The diagram of Fig. 1 shows schematically how the four frequencies are assigned to the two channels in the case of the Twinplex system. The four lines f_1 , f_2 , f_3 and f_4 represent the four frequencies arranged symmetrically with respect to a central channel frequency indicated by a dash-dot line. The channel A is characterized in that during the transmission of the space signal T the frequency (f_1 or f_2) lies, for example, on the left side of the central channel frequency, and in case of the transmission of the mark signal Z, the frequency (f_3 or f_4) lies on the right side of the central channel frequency. Whether the frequency lies at f_1 , f_2 , f_3 or f_4 depends upon the other channel signal B at any particular instant. The space signal T for the channel B is given by the frequency f_1 or f_3 and the mark signal Z by the frequencies f_2 or f_4 . Whether the frequency f_1 or f_3 occurs depends upon the signal in channel A. In the Diplex system, the assignment of the four frequencies to the channel A is the same as in the Twinplex system. However, the frequencies in case of the channel signal B are assigned as schematically indicated in the diagram of Fig. 2.

In case of the Twinplex system according to Fig. 1, the whole signal at the transmitter side is composed of the two channel signals A and B in such a manner that the transmitter for the channel signal A supplies a current of twice the value (+2, -2 in the diagram Fig. 3) as the transmitter for the channel signal B (+1, -1 in the diagram Fig. 3) to the common load resistance R of the direct current circuits. As a result of this, four different voltages (+3, +1, -1, -3) are obtained at the common load resistance R as a function of the instantaneous signals of the channels A and B, said voltages controlling the frequencies of the transmitter, for example, by means of a reactance tube. In this case, the same relation as mentioned in the foregoing with reference to Fig. 1 exists between the voltages and the signals in the two channels A and B. It has been known heretofore to separate the received four frequencies from one another, preferably, in the low frequency circuits by means of filters. It has

2

also been known to save filters by using members with frequency-dependent phase rotation, as well as phase modulation.

These known systems have the disadvantage that it is possible only to receive signals transmitted with a certain separation between the four frequencies, said separation generally amounting to 400 cycles. More recently transmitters have been known in which a larger or smaller frequency separation is used.

It has been known to omit filters when separating two channels, and to obtain four different D.C. voltages corresponding to four signal frequencies by frequency demodulation. A discriminator with two oppositely polarized sets of rectifiers serves as the frequency demodulator, so that two intersecting demodulation characteristics are obtained. Thus, actually, there are two oppositely acting discriminators with common oscillator circuits. The signal of the channel A is determined by the polarity of the output voltage of the one discriminator. Three biased tubes acting as switches are employed to obtain the channel B. One of the tubes will be opened by one discriminator in response to the frequency f_1 and the second tube will be opened by the other discriminator in response to the frequency f_3 . In order to prevent the second tube from being opened by the frequency f_4 , the output voltage of the second discriminator is rendered ineffective during the occurrence of said frequency f_4 by means of a third switching tube controlled by one rectifier of the second discriminator. In this way, filters are avoided; however, the biasing voltages of the three switching tubes have to be separately adjusted in case of a change in the shift between the four frequencies.

The invention shows simpler circuit arrangements which, in addition, make it possible to adapt the receiver to a changed frequency shift solely by adjusting a single bias voltage.

The invention relating to the reception of two channels, transmitted from the same transmitter by means of frequency shifts, provides that one discriminator having a single demodulation curve serves for frequency demodulation and also supplies a direct current voltage to a symmetrical amplitude clipping device in order to obtain a signal for channel A for which the polarity of the output voltage of the discriminator determines the space or mark signal. The clipping level of this symmetrical amplitude clipper device is equal to or smaller than the direct current voltages which correspond to the two frequencies nearest the central channel frequency. The other channel B of the output voltage of the discriminator is demodulated, depending upon the assignment of the four channel frequencies to the mark and space signals of this channel B, so that only the latter channel is produced. In case of the Twinplex system, the demodulation is carried out in such a manner that a certain portion of the output voltage of the discriminator is added to the output voltage of the amplitude clipper, while in the Diplex system, the demodulation takes place in another manner, as will be explained below.

These and other objects and advantageous features of this invention will be apparent from the following detailed description and drawings, appended thereto, wherein merely for the purposes of disclosure non-limitative embodiments of the invention are set forth.

In the drawings:

65 Figs. 1, 2 and 3 (already referred to in the foregoing) are diagrams, which indicate schematically the distribution of the four frequencies to the two channels in case of the Twinplex system and of the Diplex system, respectively.

70 Figs. 4, 5 and 6 are three examples of circuit diagrams illustrating schematically how the invention can be applied to the Twinplex system.

Fig. 7 is an example of a circuit diagram showing schematically the application of the invention to the Diplex system.

In Fig. 4, relating to the Twinplex system of Fig. 1, a discriminator D is used in accordance with the invention, said discriminator being connected to the channel frequency voltage. The load resistance of this discriminator is a variable potentiometer S_p , and the discriminator applies a relatively high set of output voltages thereacross, i.e., +30 v., +10 v., -10 v., or -30 v. An amplitude clipper comprising a series resistance R_1 and two diodes A_1 and A_2 being of opposite polarity serves to obtain the channel signal A, the cathode or anode of said diodes being positively or negatively biased by a voltage which can be equal to, but in this case is smaller than the direct current voltages, +10 v. and -10 v., corresponding to the two frequencies nearest the central channel frequency (f_2 and f_3) in Fig. 1. The resistance R_1 is inserted in series to increase the clipping action of this amplitude clipper. The output voltage of the amplitude clipper is fed to the tube V_1 which is operated by means of an anode bias arrangement. The channel signal A is derived from the cathode of this tube V_1 . This tube V_1 acts as a low impedance device. The application of an amplitude clipper to obtain the signal A is possible, because according to the diagram of Fig. 1 the direction of the shift of the instantaneous frequency from the central frequency determines the mark and space signals of the channel A. Therefore a small deviation, at most up to the frequencies f_2 and f_3 in Fig. 1, i.e. in the above example a direct current voltage of ± 0.5 voltage units is sufficient to obtain the channel signal A. These 0.5 voltage units are produced according to Fig. 4 by bias voltage sources of +2 volts or -2 volts at the amplitude clippers A_1 and A_2 to obtain the proper values for the channel signal B.

To obtain the channel signal B, the channel signal A is combined with a certain portion of the output voltage of the discriminator. This takes place in the tube V_2 . In this operation the function explained in connection with Fig. 3 is used, according to which the total signal S at the transmitter equals the sum of the channel signals A and B, i.e.

$$S = A + B$$

At the receiver, the channel signal B can be derived by subtracting the channel signal A from the total signal S, i.e.

$$B = S - A$$

This subtraction is performed in the tube V_2 by feeding to the grid the total signal S and to the cathode the channel signal A, so that the actions of these signals on the anode current are in opposite directions. In order to fulfill the last equation, the values S and A have to be brought into the correct relation to one another, which takes place by adjusting the magnitude of the total signal S by means of the potentiometer S_p . This adjustable potentiometer serves simultaneously to permit reception of transmitters having different frequency shifts by correctly adjusting the slide contact. If the slide contact is properly adjusted to the voltages indicated in Figure 4, the following equations are obtained from the last equation for the above numerical example:

$$\begin{aligned} +3 - (+2) &= +1 \\ +1 - (+2) &= -1 \\ -1 - (-2) &= +1 \\ -3 - (-2) &= -1 \end{aligned}$$

It can be seen from this, that the signal $Z(+1)$ occurs in the channel B independently of whether the frequency $f_4(+3)$ or $f_2(-1)$ is received. The same is true for the signal $T(-1)$ in an analogous manner.

The Twinplex circuit of the embodiment of this invention shown in Fig. 5 operates according to the same principle as the circuit of Fig. 4. However, in this case the reversing of the terminals of the one voltage is not ob-

tained by controlling of the cathode of the one tube. Rather the load resistance S_p of the discriminator D is tapped at the center. This makes it possible to superimpose the channel A and the total signal S to obtain the channel B by controlling the two tubes V_3 and V_4 at the grid and operating into a common plate resistance R_a .

In the Twinplex system shown in Fig. 6, the channel B is obtained in a different manner from that in Figs. 4 and 5. The obtaining of the channel B is based upon the fact that, for example, the positive voltages supplied from the discriminator D, said voltages corresponding to the frequencies f_3 and f_4 in Fig. 1, are moved over into the range of the negative voltage to such an extent that the voltage corresponding to the frequency f_3 occupies the same location as the voltage corresponding to the frequency f_1 and that the voltage corresponding to the frequency f_4 occupies the same location as the voltage corresponding to the frequency f_2 . Then the space signal T appears at the output of the circuit independently of whether this signal is transmitted under the action of the channel A by the frequency f_1 or by the frequency f_3 . The same is true in an analogous manner for the signal condition Z. A sweep circuit K is used in Fig. 6 to select the channel signal A, or to select the channel signal B. The sweep circuit K is simultaneously suited to obtain the channel signal A, because it has also the clipping quality of a symmetrical amplitude clipper.

The mentioned displacement for obtaining the channel signal B is carried out by means of electronic tubes V_5 , V_6 and V_7 , V_8 controlled by the output voltage of the discriminator D via the sweep circuit K, the outputs of said electronic tubes being interconnected and operating into a common anode resistance R_a . The inputs to these four tubes, operating as two electronic switches, are at grids of the tubes V_6 and V_8 . These switch tubes V_6 and V_8 are controlled by the tubes V_5 and V_7 and by the circuit K in such a manner that, in case of a negative output voltage of the discriminator, the switch tube V_6 becomes operative, and in case of a positive output voltage, the switch tube V_8 becomes operative. This rendering operative is caused by the cut-off of the tubes V_5 or V_7 . The input to the switch tube V_6 is directly connected with the slide arm of the potentiometer S_p , while an auxiliary direct current bias fed from the voltage source Q is inserted in the electric connection between the input of the other switch tube V_8 and the potentiometer S_p , said auxiliary direct current bias being adjusted and polarized in such a manner that the moving-over described in the foregoing takes place. This moving-over occurs in accordance with the equations given for grid feed to the tube V_8 . As can be seen, the grid of the tube V_8 is controlled by the same voltages -3 and -1 as the grid control of the tube V_6 . In this embodiment of this invention the receiver is adjusted to the shift separation of the four frequencies used in the transmitter by adjusting the slide contact of the potentiometer S_p or by adjusting the auxiliary direct current bias supplied by the voltage source Q.

Fig. 7 shows an application of the invention to the Diplex system according to the diagram of Fig. 2. The channel signal A is obtained by means of an amplitude clipper as in the foregoing, since the Diplex system corresponds to the Twinplex system with respect to the channel A. To obtain the channel signal B of Fig. 2, in the circuit of Fig. 7, the symmetrical distribution of the four frequencies representing the signals of the channel B with respect to the central frequency is utilized. The following is derived therefrom. If the output voltage of the discriminator, corresponding to the instantaneously transmitted frequency, surpasses a certain threshold value lying between the voltages of the outer frequencies, the signal T has to appear at the output of the signal channel B. The signal Z has to be located below this threshold value. Two biased diodes G_1 and G_2 are used to carry out this operation, said diodes becoming conductive above the mentioned threshold value and

thereby permitting the output voltage of the discriminator to pass to the grids of the tubes V_9 or V_{10} . The threshold value in case of the diode G_1 is obtained by a negative bias voltage at the anode by means of the voltage divider a, b , and in the case of the diode G_2 by a positive bias voltage at the cathode by means of the voltage divider c, d . The grid voltages of the two tubes V_9 and V_{10} below the threshold value given by these biasing voltages are determined by the biasing voltages on the two diodes G_1 and G_2 . The tube V_9 operates in accordance with the anode bias and controls the cathode of the tube V_{10} via a cathode resistance Rk common to the two tubes. The channel signal B is derived from the anode resistance Ra of the tube V_{10} .

If according to Fig. 2, for example, the frequency f_4 is transmitted, said frequency produces a voltage of +3 volts at the slide arm of the potentiometer Sp , so that the diode G_2 becomes conductive and the grid biasing voltage of the tube V_{10} increases 1 volt and the anode voltage of the tube decreases due to the correspondingly increasing anode current (space current). If the frequency f_1 is transmitted and accordingly a voltage of -3 volts is produced at the side arm of the potentiometer Sp , the diode G_1 becomes conductive and the grid voltage of the tube V_9 becomes more negative by one volt. As the result of this, the cathode voltage of the tube V_{10} is decreased about one volt corresponding to an increase of the grid voltage of about +1 volt of the tube V_{10} . Thus, the anode voltage of the tube V_{10} is also lowered, when the frequency f_1 is received (space current).

Finally, a possibility for reception by the Twinplex system will be briefly explained in the following. The channel A is obtained by amplitude clipping as described in the foregoing. To obtain the channel signal B use is made of the fact that in Fig. 1 the mark and space signals in the two separate channels are the same in the case of the frequencies f_1 and f_4 , and are opposite in the case of the frequencies f_2 and f_3 . In order to carry out this receiving method, the circuit according to Fig. 7 for the Diplex system is first employed. The output B of this circuit arrangement controls two electronic switches in such a manner that one switch is closed at the frequencies f_1 and f_4 , and the other switch is closed at the frequencies f_2 and f_3 . The inputs to these switches are connected to a sweep circuit controlled as in Fig. 6 by the output voltage of the discriminator in such a manner, that one conductivity condition is obtained in case of the frequencies f_1 and f_2 and another conductivity condition in case of the frequencies f_3 and f_4 . This sweep circuit serves simultaneously for obtaining the channel signal A. The channel signal B is derived from the common output of the two electronic switches.

Although in accordance with the provisions of the patent statutes this invention is described as embodied in a concrete form and the principle of the invention has been explained together with the best mode in which it is now contemplated applying that principle, it will be understood that the elements, combinations and/or circuits shown and described are merely illustrative and that the invention is not limited thereto, since alterations and modifications will readily suggest themselves to persons skilled in the art without departing from the true spirit of the invention or from the scope of the annexed claims.

The expression "sweep circuit" means in the foregoing specification and in claim 5 a circuit of the kind of a so-

called trigger-circuit or a bistable circuit as the known flip-flop circuit of the Eccles-Jordan type.

I claim:

1. An apparatus for receiving two telegraphic signals both transmitted by frequency-shift mark and space transmission employing four degrees of shift symmetrically arranged about a center frequency, and separating the signals into channel A and channel B signals comprising, a discriminator to demodulate the signals and provide a total signal containing A and B components and having four different direct current voltages of polarities determined by the direction of frequency shift with respect to said center frequency; an amplitude clipper to receive output from said discriminator and eliminate voltage values in excess of the values corresponding with the smaller shift voltages to produce a signal operative in channel A; potential divider means connected to said discriminator and adjustable to supply a signal S proportional to the discriminator output; and mixer means to receive signals S and A and combine these signals to produce an arithmetic resultant constituting the signal operative in channel B.
2. An apparatus as set forth in claim 1, the signals being related by the formula $B=S-A$.
3. An apparatus as set forth in claim 1, said mixer means comprising an amplifier tube having an anode circuit from which the signal B is derived and having a grid circuit to which the signal S is applied and a cathode circuit to which the signal A is applied.
4. An apparatus as set forth in claim 1, said potential divider means having a grounded center and being fed at its ends by said discriminator, said clipper being fed from one end of said divider means, and in turn producing said signal A; two amplifier tubes having their anodes connected in parallel to produce the signal B, the signal A being connected to the grid of one amplifier tube, and the signal S being derived from said voltage divider means on the other side of the center from which the signal A was derived, and the signal S being connected to the grid of the other amplifier tube.
5. An apparatus as set forth in claim 1, said amplitude clipper being a sweep circuit K, the output of one side of which comprises the channel signal A, and the sweep-circuit output being control voltages of constant amplitude with opposite polarities dependent upon the instantaneous direction of frequency shift; two amplifier tubes; and two control tubes connected to said amplifier tubes to control whether the former are conductive, said sweep circuit output voltages being connected to actuate said control tubes, and the amplifiers having their anode circuits connected in parallel to a common load resistance, across which is produced the channel signal B, the grid of one amplifier being connected to the signal S and the grid of the other amplifier being connected to the signal S through a source of constant direct current potential Q, which subtracts from the signal S a constant potential equal to the absolute values of the voltage S for a maximum frequency shift plus the voltage S for a minimum frequency shift.
